UNITED STATES PATENT OFFICE.

MILTON M. KOHN, OF NEW YORK, N. Y.

WORK SUPPORT FOR HEATERS.

Original application filed June 19, 1922, Serial No. 569,346. Divided and this application filed June 20, 1923. Serial No. 646,679.

To all whom it may concern:

Be it known that I, MILTON M. KOHN, a citizen of the United States, residing in New York, in the county of New York and State of New York, have invented certain new and useful Improvements in Work Supports for Heaters, of which the following is a specification.

This invention relates to improvements in work supports and appliances used in connection with burners and heaters, the same being a division of my application for patent filed June 19, 1922, Serial No. 569,346.

One of the objects of the invention is to provide a radially armed support or spider which may be firmly secured upon burner tubes of varying sizes, the arms of the support being inclined and provided with corrugations adapted to center and maintain various articles over a gas flame, these arms terminating in members suited to engage and centrally support an oven or heat retainer used in connection.

Another purpose is to produce devices engageable with the support whereby the heat rising from a gas flame is disseminated and equalized over a considerable area, enclosed or otherwise, so as to equally affect objects in a uniform manner.

These several aims and others which will appear as the description progresses, are accomplished by the novel construction and arrangement of parts hereafter described and shown in the accompanying drawing, in which:—

Figure 1 is a plan view of the spider-like support in detail.

Figure 2 is a side view of the same.

Figure 3 is a partial side elevational, partial sectional view of a work supporting device for diffusing the action of a flame.

Figure 4 is a bottom plan view thereof.

Figure 5 is a plan view of a modified form of heating plate.

Figure 6 is a partial side and sectional view of the same.

Figure 7 is a bottom plan view thereof.

Figure 8 is a partial side elevational, partial sectional view of another modification in construction.

Figure 9 is a bottom plan view of one form of the spider hub.

Figure 10 is a like view of a modified form of the same.

Figure 11 is a plan view of the spider hub.

means for supporting various articles and devices for deflecting and uniformly distributing the heat as further on described.

Said spider consists of a central ring or hub 50, from which extends radial risers 51 turned outwardly at a uniform height, presenting inclined arms 52 having serrations 53 on their upper, gradually rising surfaces, these arms being offset downward to 65 present outwardly bevelled faces 54 and terminate in outstanding support elements 55.

The serrations 53 form in effect steps or ledges adapted to center discs or like elements over the gas flame and also to prevent such discs or plates from slipping, and the supports 55 are suited to receive and hold a circular oven or heat containing cover element in an obvious manner.

The crown ring 50 may be provided with cross bars 56, as shown in Fig. 9 or with inreaching projections 57 as indicated in Fig. 10 or an annular flange 57' as shown in Fig. 2, but in all cases said bars or 80 projections are preferably of triangular cross section, presenting wedge-shaped lower edges in order to avoid interrupting the flow of fuel gas through the tube on which they rest.

Various means for maintaining the spider in rigid position relative to the burner tube may be used, in one of which the hub 50 is extended downwardly to loosely fit over the top of the burner tube and provided with thumb clamp screws to impinge upon the tube.

Work supports are shown in Figs. 3 to 10, the same to be used either with or without an oven or other form of cover as desired.

The device shown in Figs. 3 and 4 consists of a concave circular body 80, having in its lower surface a plurality of circular grooves 81 interrupted by radial grooves 100 82 tending to break the heat waves impinging upon it and near the edges are pairs of opposed lugs 83 having between them spaces 84 adapted to engage on opposite sides of each of the arms 52 to be centered 105 and held in place thereby.

Extending rigidly upward from near the edge of the plate 80 are posts 85 adjustable as to length and which can also be provided with ball or gimbal joints so that 110 the upper support or plate can be placed at any desired angle. The upper ends of

the posts 85 are fixed in a flat disc 86, presenting a level upper surface to receive work parts, this plate being perforated, as at 87, to freely permit the passage of heat and the edge at the disc 86 is preferably downturned or beaded as at 88 to prevent the flame from creeping over it.

In the modification shown in Figs. 5, 6 and 7 the lower surface of the body 80' is provided with similar grooves and lugs 83' and the spacing posts 85' are fixed in the body 80' to rigidly support the disc 86', which may be identical with that described or corrugated as shown.

In Fig. 8 the device as shown is composed of a concave plate 90 formed to produce lugs 91 engageable with the arms 52, and its edge is turned up to form a band 92 from which extends prongs 93 adapted to enter appropriate openings in the disc 94, which is similar in function to the discs already described.

The action of this device will be readily understood and appreciated, as in operation the heat from the burner impinges and breaks on the bottom plate, which is relatively small in area, and passing its edge, is transmitted to the top discs or plates from all directions, heating the work in a uniform and thorough manner.

It is preferred that the material used in construction of the devices be non-oxidizable in character and it will be clear that when used in connection with an oven the articles supported will be equally heated at all points.

While metal will ordinarily be used in the construction of these supports, there are many cases, particularly for chemical work, where it may be not only desirable but necessary to make the deflectors of some ceramic or refractory material.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:—

1. A work support for gas burners comprising a spider having radiating arms and a crown ring adapted to engage the top of a burner tube, means on said arms adapted to prevent sliding movement of an article placed thereon, and means at the ends of said arms for supporting a cover.

2. A work support for gas burners comprising a ring suited to engage the end of the burner tube, means for removably se-

curing said ring thereto, a plurality of risers integral with said ring, upwardly inclined 65 radial arms formed with said risers, corrugations on the upper surfaces of said arms, and horizontal extensions on the ends of said arms in a plane below said corrugations.

3. A work support for gas burners comprising a three armed spider, means on said spider arms for engaging a cover, supporting elements extending transversely across said spider, said elements being of wedge-shaped cross section adapted to seat on the top of the burner tube, and means for rigidly engaging said spider to the burner tube.

4. A work support for gas burners comprising a spider having radiating arms, means on said arms adapted to prevent sliding movement of an article placed thereon, support means for casings at the ends of said arms, said spider having a hub at the inner ends of the arms suited to engage a burner, and means in said hub adapted to engage upon a burner tube.

5. A work support for gas heaters comprising a spider, a removable concave body having circular and radial grooves in its lower surface, means for attaching said body to said spider over a heater, a level disc of larger diameter than said body, and connections between said body and disc whereby they are held in adjustable spaced relation.

6. The combination with a gas heater and an armed spider secured thereover, of a concave body having a serrated under surface, lugs extending therefrom adapted to engage the arms of said spider, a flat disc of larger area supported at a spaced entrance above said body, and a band on said body enclosing the space between the body and disc.

7. The combination with a gas heater and an armed spider secured thereover, of a removable deflecting body having a serrated under surface, lugs extending therefrom adapted to engage the arms of said spider, a disc having an undulating surface of larger area than said body, and connections between said disc and body whereby they are held in spaced relation.

8. The combination with a gas heater and an armed spider secured thereover, of a separable removable deflecting body having a serrated under surface, lugs extending therefrom adapted to engage the arms of said spider, and a flat disc of larger area supported in adjustable spaced relation to said body.

In testimony whereof I have signed my name to this application.

MILTON M. KOHN.
